PHONOGRAPH PICKUP

Ray F. Corbett, Lewisburg, Pa., assignor to Westinghouse Electric Corporation, East Pittsburgh, Pa., a corporation of Pennsylvania

Application May 10, 1946, Serial No. 668,659

3 Claims. (Cl. 179—100.41)

1

My invention relates to sound reproducing devices and, in particular, relates to arrangements for producing an output current varying in amplitude and frequency in correspondence with a groove cut on a phonographic record. One of the principal features of my invention is the employment of the variations in resistance of metallic wires which are impressed with longitudinal strains by a needle following the groove in the phonograph record.

One object of my invention is to provide a novel type of sound reproducing head for phonographs.

Another object of my invention is to provide a phonograph sound reproducing head in which the mechanical movements of the needle or stylus following the groove in the record are caused to vary the resistance of a metallic conductor in such a way as to produce an output current in an electric circuit which corresponds in frequency and amplitude with the periodic fluctuations of the sound groove.

Still another object of my invention is to provide a phonograph sound head in which movements of the needle or stylus in one direction cause variations in the output current of an electrical network embodying resistors strained by said movements, but in which movements of the stylus or needle in directions at right angles to the first-mentioned direction produce substantially no fluctuations in the output current.

Still another object of my invention is to produce a phonograph pick-up in which the output current is unaffected by movements of the stylus except in the direction of one of three rectangular coordinated axes in space.

Other objects of my invention will become apparent upon reading the following description, taken in connection with the drawing in which:

Figure 1 is a schematic view, partly in perspective, illustrating a preferred embodiment of my invention; and

Fig. 2 is an end view of the arrangement shown in Fig. 1.

Referring in detail to the drawing, my phonograph pick-up comprises a horizontal support tone arm 1 adapted to be supported on the frame of a phonograph having a turntable rotating about a vertical axis on which disk-type sound records may be carried in accordance with a practice now conventional in the phonograph art. The arm 1 is adapted to be swung on the means supporting it adjacent to the phonograph frame so that the stylus or needle 2 rests in the sound groove of a rotating phonograph disk. As the disk rotates, the needle 2 is moved by the curva-

ture of grooves in the disk in the direction indicated by the arrows 3 in Fig. 2.

The needle 2 is held in a chuck 4 which is mounted on a small plate 5 of fiber or other suitable material. The plate 5 is supported from the arm 1 by a pad 6 of rubber or other suitable elastic material which is sufficiently flexible so that the needle 2 can move in the directions of the arrows 3 far enough to follow the fluctuations of the groove in the phonograph disk. The pad 6 is seated between the arms 7 and 8 of the support member 1 and is held in position thereon by a top plate 9 of fiber or other suitable insulating material. Supported on the upper surface of the top plate 9 is a wire 11 of some suitable material and having the configuration shown in heavy outline in Fig. 1. The wire 11 may conveniently be made up in the form shown from two subdivisions 12 and 13, each in the form of a hair pin. Two arms of the hair pins are connected to each other and to a center lead 14' consisting of any suitable conducting wire, which may be cemented or otherwise fastened for a portion of its length to the support arm 1. The hair pins 12 and 13 then have their closed ends bent around the support arms 7 and 8, as indicated in Fig. 1, and are so proportioned that their closed ends project into contact with the lower surface of the plate 5. These ends are then attached, for example, by a suitable adhesive to the plate 5. The free ends of the hair pins 12 and 13 are connected to suitable lead wires 14 and 15, a portion of which may be cemented to the arm 1, and which leads are connected to the outer terminals of a transformer winding 16, preferably through a flexible cord. The lead 14' is connected to one terminal of a battery or other source of voltage 17, the other terminal thereof being connected to the mid-point of the winding 16. A secondary winding 18 cooperates with the winding 16 to produce output currents which may be fed through a suitable amplifier to a loud speaker or other sound reproducing device.

When the stylus 2 follows the groove in the rotating phonograph disk, it is alternately moved from side to side in the direction of the arrows 3, i. e. along a radius of the record, with a frequency corresponding to the sound pressure modulation of the record groove of the phonograph disk. The hair pins 12 and 13 are mounted on the plates 8 and 9 under tension so that they respectively exert a force tending to move the plate 5 to the left and to the right in Fig. 2. The rest-position of the needle 2 is naturally that in which these two forces are equal and opposite to each

other. When now the stylus 2 is moved either to the left or to the right in the direction of the arrows in Fig. 3, it will increase the longitudinal stress in one of the hair pins 12, 13 and decrease such stress in the other hair pin. The resistance of the hair pins 12 and 13 and the number of turns in the respective halves of the winding 16 are so proportioned initially that in the undisplaced position of the stylus 2, the currents sent by the voltage source 17 through the winding 16 are equal and opposite to each other in magnetic effect on the core associated with the winding 16. As a result, the flux set up in said core is substantially zero.

When now the stylus 2 increases the stress in, let us say the hair pin 12, and decreases the stress in the hair pin 13, the resistance of the hair pin 12 increases and the resistance of the hair pin 13 decreases and, consequently, the current flowing through one-half of the winding 16 increases while that flowing through the other half decreases, with the result that a magnetic field is set up in the core associated with the winding 16.

At a time corresponding to one-half period of the sound pressure wave recorded by the groove on the phonograph record, the stylus 2 will be moved back through its undisplaced position and receive a displacement in the opposite direction, thereby increase the longitudinal stress in the hair pin 13 and decreasing such stress in the hair pin 12. As a result, the current through the respective halves of the winding 16 will have been altered so that these windings produce a magnetic field in the core associated with the winding 16 which is in the opposite direction to that described in the presaid paragraph. The dimensions and elastic characteristics of the pad 6 are so proportioned that, for the maximum lateral excursions of the stylus 2 under the impress of the phonograph record groove, the variations in resistance of the hair pins 12 and 13 due to changes in the mechanical stress imposed thereon by plate 5 are substantially proportional from instant to instant to the displacement of the stylus 2 from its zero or undisplaced position. The resistance of the hair pins 12 and 13 is likewise made large enough so that it controls the reactance variation of the winding 16 at all the frequencies of sound which the phonograph record carries. As a result of this arrangement, the strength of the magnetic field in the core associated with winding 16 will, at any instant, be proportional to the displacement of the stylus 2 from its zero position.

In short, a magnetic flux is produced in the core associated with winding 16 which varies in amplitude and frequency in conformance with the fluctuations of the groove in the phonograph disk. This magnetic flux will set up in the winding 18 a voltage which likewise varies at the frequency of the lateral displacements of the stylus 2 by the phonograph groove. Where the lateral fluctuations of the phonograph groove are perfectly proportional at all sound frequencies to the instantaneous amplitude of the sound, the voltage produced by the winding 17 will be proportional both to the product of the amplitude of the sound record by the frequency of its pitch; and in such instances it may be desirable to provide a suitable compensating network of a type well known to those skilled in the art in the output circuit of the winding 18 to render the current therein proportional strictly to the instantaneous amplitude of the fluctuation of the

groove on the phonograph record. However, in actual practice, the amplitude of fluctuation of the groove on the phonograph record is not strictly proportional to the loudness of the sound being recorded, but is less at higher sound frequencies than at lower sound frequencies. This fact produces what may be called an automatic compensation for the increase in the output voltage of the winding 18 at high pitches so that for many purposes the above-mentioned compensating network may be greatly simplified or even eliminated.

Fluctuations in the resistances of the hair pins 12 and 13 which result in production of a magnetic flux in the core associated with winding 16 are those which represent differences in the resistances of hair pins 12 and 13. In other words, anything which produces a simultaneous increase in resistance of the hair pins 12 and 13 decreases the current through the two halves of the winding 16 equally and leaves its magnetic effect on the core associated with unaltered. Thus it is that while lateral movements in the direction of the arrow 3 of the stylus 2 increase the resistance of hair pin 12 while they decrease the resistance of hair pin 13 and thereby result in the production of magnetic fields in the core associated with winding 16, movements of the stylus 2 in any direction normal to the arrows 3 produce equal increases or decreases in the resistance of the hair pins 12 and 13 and hence produce no change in the magnetic field in the core associated with winding 16. In other words, vertical movements normal to the plane of the sound record produce no output currents in the winding 17 and, similarly, any fluctuating drag of the stylus 2 along the phonograph disk produces only equal changes in the resistance of the hair pins 12 and 13 and hence produces no output current from the winding 17. Thus it is that with my arrangement it is only movements of the stylus 2 along one of three rectangular axes in space that produce output currents in the winding 17; and movements along the other two of the three coordinated axes produce no output currents from the winding 17.

While I have shown the resistors 12 and 13 as made up in the form of hair pins, it will be evident to those skilled in the art that these wires may be given any other configuration so long as lateral movements of the stylus 2 act only to increase the longitudinal stress in one wire and decrease the longitudinal stress in the other wire. Many other configurations meeting these conditions will be apparent to those skilled in the art.

55 I claim as my invention:

1. A sound pick-up device for phonographs comprising a tone arm, a stylus elastically supported relative to said tone arm, two hair-pin shaped resistors having their closed ends mechanically connected to said stylus and having their open ends mechanically connected to said tone arm, means for causing electric currents to flow in multiple through said conductors, means for causing the electrical effect of said currents to neutralize each other in an output circuit when said stylus is in a predetermined position relative to said tone arm, and to produce a net effect in an electrical output circuit in other positions of said stylus relative to said tone arm, and means 60 for causing said conductors to exert oppositely-directed mechanical forces on said stylus.

2. In a phonograph pick-up a tone arm having a longitudinal axis, a stylus supported substantially perpendicular to said axis and provided with 65 means for permitting its movement in a direction

perpendicular to said axis and to the first-mentioned direction, a pair of hair-pin shaped conductors having their closed ends supported on said stylus and having their open ends supported on said tone arm, said hair-pin shaped conductors being positioned so that longitudinal stresses therein exert opposing forces on said stylus in directions parallel to said movement, means for producing current flow through said conductors in multiple with each other, and means for opposing the electrical effects of said currents on an output circuit.

3. In a phonograph pick-up a tone arm having a longitudinal axis, a stylus supported substantially perpendicular to said axis and provided with means for permitting its movement in a direction perpendicular to said axis and to the first-mentioned direction, a pair of hair-pin shaped conductors having their closed ends supported on said stylus and having their open ends supported on said tone arm, said hair-pin shaped conductors being positioned so that longitudinal stresses therein exert opposing forces on said stylus in directions parallel to said movement, means for producing current flow through said conductors

in multiple with each other, means for opposing the electrical effects of said currents on an output circuit, and means for causing said hair-pin shaped conductors to exert substantial stresses in opposite directions on said stylus in the undisplaced position thereof.
